UNITED STATES PATENT OFFICE.

JOHN NEWBERRY REYNOLDS, OF GREENWICH, CONNECTICUT, ASSIGNOR TO WESTERN ELECTRIC COMPANY, OF NEW YORK, N. Y., A CORPORATION OF ILLINOIS.

SEQUENCE-SWITCH.

1,164,212.

Specification of Letters Patent. Patented Dec. 14, 1915.

Application filed March 1, 1913. Serial No. 751,357.

To all whom it may concern:

Be it known that I, JOHN NEWBERRY REYNOLDS, a citizen of the United States, residing at Greenwich, in the county of Fairfield and State of Connecticut, have invented a certain new and useful improvement in Sequence-Switches, of which the following is a full, clear, concise, and exact description.

This invention relates to a circuit controlling device whereby means are provided for automatically controlling a series of circuit changes either of the same device or of different devices in a definite and predetermined sequence.

15 One of the objects of this invention is the provision of a device of this character whereby a large number of circuit changes may be effected with precision by a small amount of apparatus.

20 Another object of this invention is the provision of a device of this character in which the contacts are readily accessible for examination and adjustment.

Other objects and advantages will appear 25 as the description of the device progresses.

A device of this character may be used for controlling electrical apparatus of many kinds but is particularly designed for use in automatic telephone systems wherein certain circuit changes must be effected in a 30 definite order.

Briefly described, the device consists of a frame in which a shaft is rotatably mounted. A metallic disk is non-rotatably mounted on 35 this shaft. This disk may be provided with projections at the circumference and integral portions projecting from the surface on both sides, whereby contacts are provided. Generally a plurality of these disks will be 40 mounted in spaced relation on the shaft. Mounted on the frame is a plurality of brushes which are arranged to coöperate with the contacts of said disk or disks upon rotation of the shaft.

45 For a more complete description of the embodiment of the invention, herein disclosed, reference is now made to the accompanying drawings, wherein—

Figure 1 is a side elevation of the device 50 partly in section; Fig. 2 is a sectional view taken on the line 2—2 of Fig. 1; Fig. 3 is a perspective view of the positioning device detached; Fig. 4 is a perspective view of two adjacent sets of brushes with their spacing arms; and Fig. 5 shows two adjacent

disks, one of said disks being removed from the shaft to show the arrangement of the spacing blocks between the disks.

Referring now to the drawings, 1 represents a frame member having the ends 2 and 3 bent at right angles thereto. The member 1 carries at one edge thereof a shelf or ledge 4 for a purpose to be hereinafter described. The shaft 5 is rotatably mounted between the members 2 and 3 and has a projecting portion 6 at one end thereof of reduced dimensions, mounted in a bearing 7 in the frame member 3. The other end of the shaft is reduced in diameter and screw threaded. This screw threaded portion is provided at the end thereof with a depression 8 adapted to receive the projection 9 at the end of the screw threaded member 10. This member 10 passes through an opening in the frame member 2 and is adjustably secured in position by the nuts 11 and 12 on opposite sides of the frame member.

Non-rotatably mounted on the shaft 5 in spaced relation is a plurality of metal disks 13. Spacing sleeves 14 are provided between these disks. Each of these sleeves is provided with a squared projection 15, which is received by the opening in its respective disk 13, whereby the said disk is held from rotation upon and is insulated from the shaft 5. This projection 15 is of greater length than the thickness of the disk 13 and the portion which projects beyond said disk is received by a depression 15' formed in the adjacent end of the next sleeve 14.

Each of the disks 13 is formed at the circumference thereof with one or more segmental projections 17 as shown most clearly in Fig. 5. It is to be understood, of course, that as many of these projections may be provided as the use to which the switching member is to be put requires. A series of cam like contacts is also provided on each face of each of these disks 13. These contacts may be formed by slotting a portion of said disks on three sides and punching the tongue shaped portion which is thus partially severed from the plate outwardly to form a cam which will occupy a plane beyond the surface of the disk. In practice, one of these series may be provided immediately adjacent the circumference of the disk by merely cutting L-shaped slots in the disk near the circumference and punching the metal thus partly severed outwardly, as

shown most clearly at 16 in Fig. 5, of these contacts may be produced by merely punching the metal outwardly without forming a circumferential cut as shown at 49. The 5 series of contacts on the opposite face of the disk is formed at a lesser distance from the shaft and it is found desirable that the metal be severed on three sides by a U-shaped cut, as shown at 17, although obviously this inner series could be formed by punching without cutting, if desired. In a switch of this character it has been found desirable to provide a structure whereby a snap or instantaneous break will be produced between 10 the brushes and their contacts. This is accomplished, as to the outer series of contacts, by terminating each of said contacts in a radially extending edge and, as to the two inner series of contacts, by providing radial 15 cuts, the metal preceding which is projected to form the contacts. This combines with the tangential arrangement of the brushes to produce the desired result, whereby the circuit connections may be terminated at 20 precisely the desired instant. A switch of this character will have a plurality of rotary positions, in the embodiment herein shown eighteen being provided, and the contacts of the several disks should be so arranged 25 that they will be definitely positioned under their respective brushes when the device occupies some certain rotary position. Obviously, contacts will not in general be provided in any one series for each 30 of the positions of the switch but only such contacts will be provided as are necessary to effect the circuit changes desired. In certain instances contacts extending over two or more rotary positions of the switch may be 35 found desirable. This may be accomplished by forming certain of the contact segments of greater extent, as shown at 48, or by making certain of the punched out contacts longer, as shown at 49.

40 Mounted on the ledge 4 and projecting tangentially to the disks, in a position to co-operate with these series of contacts, are the wipers or brushes 18, one for each series of contacts. These brushes are secured to an 45 angle clip 19 by being clamped between one leg of said clip and the plate 20 by the screws 21. The clips 19 may be secured to the ledge 4 in any desired manner but in the embodiment herein disclosed this is accomplished 50 by the screws 22 which pass through openings in the ledge 4 and are threaded into one leg of the clip 19. Each clip is arranged to support two sets of brushes of three each, that is the brushes 55 60 adapted for engagement with the contacts formed on two adjacent disks 13. It is to be understood, however, that additional series of contacts on the disks 13 and corresponding brushes may be provided, if desired. The brushes provided for engagement 65 with the contacts of one of the disks 13 are arranged at different radial distances from the shaft 5. The uppermost brush is arranged for engagement with the segmental projections at the circumference of the 70 disks. The other two brushes of the set are so positioned that they will be adjacent to and out of engagement with the opposite side surfaces of said disk but in such proximity thereto that they will be engaged by 75 contacts 16 and 17, respectively, upon rotation of the switch shaft. To more definitely position these brushes in proximity to the disk 13, a plurality of spacing members 23 may be provided. These spacing members 80 may be supported in any desired manner but, in the present embodiment are carried by arms 24 formed integral with the plate 20.

At the end of the shaft 5 adjacent to the frame member 2, a disk 25 having a cylindrical flange 26 is provided. This flange 85 may carry a scale used to indicate the various positions assumed by the switching device during one revolution thereof. Mounted near the other end of the shaft is 90 the positioning device shown in Fig. 3. The disk 27 non-rotatably secured to said shaft is provided near the circumference thereof with a series of apertures 28. Arranged to co-operate with the imperforate central portion of the disk 27 is a brush 29 and correspondingly arranged to co-operate with the apertures 28 and the contact portions intermediate thereof is a brush 30. This construction may be used to complete the circuit 95 for a controlling magnet by means of which the rotation of the switch shaft is controlled and its function is to assure the complete passage of the switch from one position of rest to the next. The disk 27 is fluted near 100 the circumference thereof, and arranged to co-operate with this fluted portion is a roller 31 held in forcible engagement with said fluted portion by the spring arm 32. The brushes 29 and 30 and the spring arm 32 are 105 supported by an angle clip 33 secured to the flange 34 on the frame member 3 by means of the screws 35. This roller and the depressions in the edge of the disk with which it co-operates act to bring the switch member to its exact position of rest in case the energizing current for the controlling magnet should be cut off too soon, thus exactly 110 positioning the contacts under the brushes. It also operates to prevent accidental displacement of the switch member.

115 Mounted adjacent to the positioning device just described, and at the end of the shaft, is a disk 36 having a plurality of substantially radially extending flexible arms 120 125 37. Each of these arms 37 is provided at the end thereof with an offset portion 38 to which is secured the annular disk 39 of magnetic material. Arranged with its edge adjacent to said disk 39 near the circumference 130

thereof and at right angles thereto is a friction disk 40 fixed to the rotatable power shaft 41. A controlling magnet 42 is located adjacent to the disk 39 and is so arranged that upon its energization said disk will be attracted against the resiliency of its supporting arms 37 into forcible engagement with the friction disk 40 and the shaft 5 will thus be rotated.

In certain cases it may be desirable to have a plurality of the disks 13 electrically united and this may be accomplished by placing a metallic collar as 43 between these disks or in any other desired manner. Each of the several disks which are mounted on the shaft are separated from each other by the spacing sleeves 14, as previously described, all being rigidly clamped together by the nuts 44 and 45 threaded on the opposite ends of the shaft 5. When it is desired that the switch member pass over certain positions so that the brushes may merely make passing engagement with their contacts or for other purposes which will be obvious to one skilled in the art, certain of the interruptions or perforations 28 corresponding to these positions may be omitted, thus holding the clutch magnet energized until the next position of rest or interruption 28 is reached. In order to prevent undue vibration by the brush 30 in passing over the interruptions 28 and the conducting portions therebetween, a disk 46 of insulating material is secured to one side of the disk 27 by rivets or in any other desired manner.

As it is obvious that many changes can be made in the details of this invention without departing from the spirit thereof, it is to be understood that I contemplate all such modifications and that the invention is to be limited merely by the scope of the appended claims.

I claim:

1. In a mechanical switch, a rotatable shaft, a metallic disk secured thereto, U-shaped slots in said disk, integral tongue

shaped portions formed thereby, said portions being projected beyond the surface of said disk whereby a series of contacts are formed and a brush arranged for successively engaging said contacts upon rotation of said shaft.

2. In an electrical switching device, a shaft, a metal disk secured thereto, a series of contact portions projecting from the circumference of said disk, a second series of contact portions projecting from the surface of said disk within the circumference thereof, and brushes, one for each series, arranged for electrical engagement with said contacts upon rotation of said shaft.

3. In an electrical switching device, a shaft, a metal disk secured thereto, a series of contact portions projecting from the circumference of said disk, a second series of contact portions projecting from the surface of said disk within said circumference, a third series of contact portions projecting from the opposite surface of said disk within the circumference, and brushes, one for each series, arranged for electrical engagement with said contacts upon rotation of said shaft.

4. In an electrical switching device, a shaft, a metal disk secured thereto, a series of contact portions projecting from the circumference of said disk, a second series of contact portions projecting from the surface of said disk within the circumference, a third series of contact portions projecting from the surface of said disk intermediate the second series and said shaft, and brushes, one for each series, arranged for electrical engagement with said contacts upon rotation of said shaft.

In witness whereof, I hereunto subscribe my name this 26th day of February A. D., 1913.

JOHN NEWBERRY REYNOLDS.
